INVENTOR

UNITED STATES PATENT OFFICE.

JOHN STROTHER THURMAN, OF INDIANAPOLIS, INDIANA.

FUEL-OIL BURNER.

SPECIFICATION forming part of Letters Patent No. 505,931, dated October 3, 1893.

Application filed November 30, 1892. Serial No. 453,656. (No model.)

To all whom it may concern:

Be it known that I, JOHN STROTHER THURMAN, a citizen of the United States, residing at Indianapolis, in the county of Marion and 5 State of Indiana, have invented certain new and useful Improvements in Fuel-Oil Burners; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to an improvement in fuel-oil burners of that class in which the oil is atomized by means of a jet of steam, and is mixed with a current of air in a suitable mixing-chamber.

20 The objects of my improvement are, to insure an equal distribution of the air on all sides of the combined oil and steam jet; and to so construct the mixer that all of its parts may be easily accessible for cleaning and 25 pairs.

The accompanying drawings illustrate my invention.

Figure 1 is a plan. Fig. 2 represents a central longitudinal section. Fig. 3 represents 30 a transverse section at —a— Fig. 2. Fig. 4 represents a transverse section at —b— Fig. 2.

In the drawings, A, indicates a jet-pipe having two longitudinal passages, B, and C, which are distinct and separate from each other. 35 Passage B, is connected by pipe D, to a source of oil supply; and passage C, is connected by a pipe E, with a source of supply of steam under pressure. That end of the jet-pipe which is farthest from the supply pipes is closed, 40 with the exception of two small orifices, F, and G, which communicate, respectively with the passages B and C. Orifice G, is arranged, preferably, parallel with the passage C, while the orifice F is inclined from the passage B 45 downward, at an acute angle, toward the orifice G; and the outer face of the end of the jet-pipe is hollowed out or cup-shaped, as at H; the purpose being to compel the oil as it passes from the passage B, to flow downward 50 across the opening G.

Mounted upon the outside of the jet-pipe A, is a semi-spherical hollow casting, I, to

which the mixing-chamber, J, is secured by screws K.

Mounted in the base of the mixing-chamber 55 is a short cylindrical sleeve, L, having in its periphery an annular groove; the arrangement being such that, when the sleeve is in position, an annular passage, M, is formed between the sleeve and the walls of the mix- 60 ing-chamber.

Mixing-chamber J, is provided, on opposite sides, with a pair of tubular projections, N, N, which communicate with a source of air supply and with the annular passage M. The 65 air-passage M, communicates with the interior of sleeve L through a series of radial perforations, O, in the sleeve, and communicates also with the interior of the mixing-chamber through a series of longitudinal perforations, P.

The arrangement of casting I, jet-pipe A, mixing-chamber J, and sleeve L, is such that the casting closes the rear end of the mixing-chamber and the end of the jet-pipe projects 75 within the sleeve.

In operation, the oil, and steam under pressure, being admitted to the passages B and C respectively, of the jet-pipe, the oil flows through opening F, downward and across the 80 opening G of the steam passage, and is atomized and blown forward into the mixing-chamber; air being thereby drawn through the tubular extensions, N, N, enters the passage 85 M, and a portion, passing through the perforations O, O, is evenly distributed on all sides of the jet-pipe and mingles with the combined steam and oil, while another portion of the air passes through the longitudinal perforations N, into the mixing-chamber and is there 90 combined with the gases from the steam and oil, which are ignited at the open end of the mixing-chamber. By this construction the air is introduced in numerous small jets, and is evenly distributed throughout the mass of 95 oil and steam, thus insuring a perfect combustion. It will be observed that, on removing the mixing-chamber from the casting I, the sleeve L may be slipped out of the base of the mixing-chamber, and the perforations 100 O and P may be easily cleaned.

I claim as my invention—

1. In a fuel oil burner, the combination with the compound jet-pipe having passages B and

C, for oil and steam respectively, and the mixing chamber having one or more air supply passages N, of the cylindrical ring L, having a peripheral groove and mounted in the base 5 of the mixing-chamber so as to form therewith an annular air passage M, said ring being provided at the bottom of the groove with a series of radial perforations O, which connect the interior of the ring with the annular 10 air passage, and provided also in its inner face with a series of longitudinal perforations P, connecting said air passages with the interior of the mixing chamber, said ring being held firmly in place between two projections 15 when chamber J and casting I are bolted together, all substantially as and for the purpose set forth.

2. In a fuel oil burner, comprising the compound jet-pipe A, having passage B, provided 20 with the inclined discharge opening F, and passage C having opening G, said openings being connected by the cup-shaped depression H, the hollow casting I, and the mixing

chamber J, provided with the cylindrical perforated ring L, and air passages N, N, which 25 communicate with, and supply the passage M, with air, said ring L being held in place between two projections when the chamber J, and casting I, are bolted together, all substantially as, and for the purpose set forth. 30

3. In a fuel-oil burner, comprising the compound jet-pipe A, having passage B provided with the inclined discharge opening F, and passage C having opening G, said openings being connected by the cup-shaped depression H, the hollow casting I, and the mixing chamber J, provided with the cylindrical perforated sleeve L, and air passages N, N which 35 communicate with a source of air supply, all substantially as and for the purpose set forth. 40

In testimony whereof I affix my signature in presence of two witnesses.

JNO. STROTHER THURMAN.
